Primary Examiner—Carol Rademaker(74) *Attorney, Agent, or Firm*—K&L Gates LLP**CLAIM**

The ornamental design for a bottle, as shown and described.

DESCRIPTION

FIG. 1 is a top, rear and left side perspective view;

FIG. 2 is a left side elevational view, the right side elevational view being a mirror image;

FIG. 3 is a front, left side corner elevational view thereof;

FIG. 4 is a front elevational view thereof, the rear elevational view being a mirror image.

FIG. 5 is a front, right side corner elevational view thereof; and,

FIG. 6 is a top plan view thereof.

The broken line showing of the pour spout and neck rings in the drawing views is included for the purpose of illustrating environmental structure and forms no part of the claimed design.
